(57) **CLAIM**

The ornamental design for a cooler, as shown and described.

DESCRIPTION

FIG. 1 is a perspective view of a first embodiment of a cooler showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a front view of a second embodiment of a cooler showing my new design;

FIG. 8 is a rear view thereof;

FIG. 9 is a right side view thereof;

FIG. 10 is a left side view thereof; and,

FIG. 11 is a top view thereof.

The dash-dash-dash broken lines in the Figures are for the purpose of illustrating unclaimed portions of the cooler and form no part of the claimed design.

The dash-dot-dash broken lines are boundary lines. It is understood that the claimed design extends to the boundary lines but the boundary lines form no part of the claimed design.

The bottom view forms no part of the claimed design.

The stippling in the Figures are not surface ornamentation and do not indicate a particular material, color, or surface finish.
